UNITED STATES PATENT OFFICE.

ARTHUR VON FRANKENBERG, OF NEW YORK, N. Y., ASSIGNOR TO FRANKART, INC.,
OF NEW YORK, N. Y., A CORPORATION OF NEW YORK.

DESIGN FOR AN ASH TRAY.

Application filed April 3, 1929. Serial No. 30,746. Term of patent 7 years.

To all whom it may concern:

Be it known that ARTHUR VON FRANKENBERG, a citizen of the United States, and resident of New York city, in the county of New York and State of New York, has invented a new, original, and ornamental Design for Ash Trays, of which the following is a specification, reference being had to the accompanying drawing, forming part thereof, in which the figure is a perspective view of an ash tray embodying my new design.

I claim:

The ornamental design for an ash tray substantially as shown.

Dated New York city, March 30, 1929.

ARTHUR VON FRANKENBERG.
